UNITED STATES PATENT OFFICE.

JAMES E. OLVIS, OF LOS ANGELES, CALIFORNIA.

VENDING MACHINE.

Application filed September 9, 1925. Serial No. 55,828.

This invention relates to a merchandise vending machine, wherein one of a variety of articles may be selected and delivered by operation of a check or coin controlled mechanism. The present invention appertains to a revoluble stock container having a number of compartments which may be selectively registered with a delivery mechanism which mechanism is actuatable by a check controlled device.

The objects of this invention are first, to provide a vending machine wherein the articles of a particular kind are stacked in a column and the column supported upon a stationary bed, the delivering device removing an article one at a time from the bottom but not supporting the stack; second, to provide compartment aligning means operable by the coin controlled mechanism; and third, to provide a mechanism of the character described having a register for the number of articles delivered.

These objects together with other objects relating to simplicity, compactness of structure, ease of manipulation, economy, durability and positiveness of structure and operation are obtained by means of the embodiment of my invention illustrated in the accompanying drawings, in which:

Fig. 1 is a vertical section through a complete machine; Fig. 2 is a section as seen on the broken line 2—2 of Fig. 1; Fig. 3 is an elevation of the lower portion of the machine as seen looking in the direction of the arrow 3 in Fig. 1; Fig. 4 is a section showing a fragment of the machine as seen on the line 4—4 of Fig. 1; Fig. 5 is an enlarged view partly in section as seen on the line 5—5 of Fig. 1 showing a detail of the registering mechanism; Fig. 6 is a vertical section on an enlarged scale showing the delivering mechanism; Fig. 7 is a view similar to Fig. 6 showing the parts in another position and more of the structure in section; Fig. 8 is a section as seen on the line 8—8 of Fig. 7; Fig. 9 is a section as seen on the line 9—9 of Fig. 7; and Fig. 10 is an enlarged sectional view showing a fragment of the delivering mechanism as seen on the line 10—10 of Fig. 7.

Referring more particularly to the structure shown in Figs. 1, 2, and 3, A indicates the base of the machine serving as a till and housing a delivery mechanism B. Rotatably mounted upon the base is the stock container C. The stock container, as shown

herein, is divided into twelve peripheral compartments and in the present instance, these compartments are similar. Each compartment is formed by side walls 11, a rear wall 60 formed by a portion of an inner cylinder 12, and a removable outer wall 13. The outer wall is preferably formed of a long glass panel which may be slipped into grooves 14 from the top. This panel may disclose 65 the articles in the compartment, and also may display matter marked thereon indicating the character of the merchandise. The compartment is covered by a lid 15 which may be of the slip-on type. The floor of the 70 container comprises a plate 16 having slots 17 of less width than the compartment so that the stack of articles may rest on the floor spanning the slot. The container is rotatably mounted upon a shaft 18 supported 75 upon a suitable pillar 19 upstanding from the base, there being bearings 20 mounted on the shaft and secured to the cylindrical wall 12 of the stock container. The base A is provided with a cylindrical wall 21 which 80 overlaps the lower end of the container wall, as best shown in Fig. 1. At each compartment and at the floor level thereof is an opening 22 in the wall for the removal of the articles being vended. There is a delivery 85 chute 23 secured to the wall 22 for receiving the articles ejected. An opening 24 for the passage of articles from the compartment to the chute is provided in a wall 22.

The delivery device is fixedly secured in 90 the base and at the chute. It is mounted upon a plate or wide bar 25 which is secured to the base. Bar 25 is formed with a return or coin rejector opening 26, and forwardly thereof a till opening 27. Mounted 95 upon the bar is a housing split to form two sections which may be secured to each other. These sections are indicated by 28 and 28'. Slots or grooves are cut in the side of the housing for slidably receiving a pull bar 100 indicated by 29. Bar 29 is formed on the under side with a recess and secured to the outer wall of the recess is a tension spring 30. The other end of this spring is secured to the bar 25. The spring tends to retract 105 the bar and hold it against an abutment 31 fixed to the bar 25. Formed in the bar 25 and opening to the upper side thereof is a coin pocket 32. The bottom of the pocket 110 has a coin discharge opening at the forward end as indicated by 33 to permit the passage of a coin therethrough. Sizing pins 34 are

2

mounted on the side walls of the pocket adjacent the rear end. They are spaced apart a distance such that they will not permit a coin of the proper size to be moved between 5 the pins, snugly engaging such a coin. They are also spaced above the bottom wall of the pocket so that a coin thinner than the normal thickness desired, will permit the coin to be slipped thereunder. Pivots mounted 10 in the housing so as to swing on a horizontal axis is a tongue 35. This tongue is disposed normally in a vertical plane and just at the opening in the lower wall of the pocket as best shown in Figs. 7 and 8. The 15 lower end of the tongue just clears the bottom wall of the pocket. Upstanding from the tongue 35 and secured thereto is an arm 36 to which is secured a tension spring 37. The tension spring is secured at its other 20 end to the housing. The tongue abuts the edge of a coin chute 38. A coin transmission chute 39 connects with the chute 38 and opens to the outside of the base adjacent the article delivery chute 23. This chute is 25 so arranged that when a coin is dropped therein, the latter will roll to the chute 38 and slide therefrom in flat position into the pocket 32. The bar 25 extends through the base at a position beneath the delivery chute 23 and is provided with a finger hole 40 so 30 that it may be grasped conveniently and pulled outwardly. Assume that a coin has been dropped in the chute 39, it will roll therealong to the chute 28 and be delivered 35 in a flat position into the pocket 32. The opening to the coin chute 39 may be so arranged that an oversize coin cannot be dropped therein. Assume that the coin is of the correct size. It will then lie flat in 40 the pocket and cannot be moved out of the rear end thereof as the posts 34 hug the coin closely and hold it in position. Upon pulling the bar 25 forwardly, the coin will 45 push the tongue 35 aside and be moved outwardly with the bar. The resistance of the tongue 35 to being moved is such that, if the coin is undersize, it will push the coin along the bottom of the pocket as the pull bar is moved outwardly, ejecting the coin at the rear 50 of the pocket and dropping it upon the wall of a chute 41, which allows the coin to slide in an upright position into a return chute 42. The return chute permits the coin to roll forwardly through an opening into the receptacle 43, thereby returning the coin to the operator.

Slidably mounted in the housing above the pull bar 25 is an operating bar 44. The rear of bar 44 has depending therefrom a post 45 disposed in pocket 32, and is arranged so that it just clears the bottom wall of the pocket. However, if there is a coin lodged in the pocket, it will engage the post and slide the operating bar forwardly as the pull bar is moved forwardly. Pivots mounted 60

cured to the forward end of bar 44 is a link 46, the upper end of which is secured to an ejector plunger later described. Mounted in the housing at the forward end is a counter 47 of a well known type having an operating arm 48. Secured to the operating arm is a rod 49 which passes through a bracket 50 mounted on operating bar 44. A compression spring 51 is disposed between the bracket and a head on the rod 49, thereby 70 tending to hold the rod in retracted position. The counter is of the well known type in which the arm 48 tends to maintain itself in forward position. The construction is such that on each complete movement of bar 80 44 the counter will be actuated to register the movement. Mounted in a way in the upper part of the housing is an ejector plunger 52. The plunger is slotted at the rear end and has the link 46 pivotally secured thereto. Pivots secured to the outer end of the plunger is a finger 53 having a leaf spring 54 on the under side tending to raise the finger. The plunger and finger are of such width that they may slide 90 into the slots 17 in the floor of the container. In Figures 6 and 7 an article 55 is shown resting on the floor of the container over a slot 17. If the ejector is moved outwardly, the finger 53 will engage and slide the latter from below the stack through openings 22 and 24 into the delivery chute 23. Assuming that there is a coin of the proper size in pocket 32 of the pull bar and the latter is pulled outwardly, the coin will ride beneath the tongue 35 pushing the latter aside and will engage post 45. The post is then caused to move with the pull bar and will move the operating bar 44 outwardly. This causes link 46 to be pulled outwardly and 100 pulls the plunger in the same direction. Finger 53 engages the lowermost article in the registering stack and ejects it into the delivery chute. Spring 30 causes the pull bar to be returned upon release of the latter by the operator, moving operating bar 44 to its retracted position, and moving the plunger 52 to its retracted position. Upon the return of the ejector plunger, finger 53 is moved downwardly sliding beneath the 110 stack. There is no weight of articles upon the ejector bar except the slight friction of the finger 53 against the bottom thereof. When the coin in pocket 32 engages the tongue 35, the latter being restrained against movement by abutting the side of chute 38 will cause the coin to be pushed into the opening 33 and to be dropped into the till in the base of the machine. The coin operating device is then ready to receive another coin. Referring particularly to Figs. 7 and 10 a detent is shown for holding the ejector in its retracted position. This detent comprises a leaf spring 55 secured to the housing and pressing against a ball 56 120 130

disposed in an opening in the housing. The ball is arranged to rest in a recess in the ejector. This holds the plunger in retracted position.

5 In order that the stock container may be properly registered so that the ejector will ride into the slot 17 without striking the sides thereof, I have provided a mechanical registering device operated by the delivering mechanism. Pivotedly mounted in the housing is a lever 56. The lever has at one end thereof a roller 57 arranged to ride upon the top of pull bar 25. The upper surface of the bar 25 has a depression 58 at the outer end, so that when the pull bar is in retracted position, roller 57 is in the depression. Upon pulling the bar outwardly, roller 57 rides out of the depression and rocks the lever 56. Lever 56 is connected to a finger 59 pivotally mounted in the housing, so that upon rocking lever 56, finger 59 will be rocked, an upward movement of roller 57 causing an outward movement of the upper end of finger 59. Mounted on 25 the housing and in a bracket is a sleeve 60. The sleeve has a washer 61 thereon engaged by a compression spring 62 which is mounted between the washer and bracket. The sleeve is engaged by the end of finger 59 and the spring 62 tends to maintain the sleeve in retracted position. Slidably mounted within the sleeve is a stem 63 having a wedge 64 as a head. A buffer spring 65 is mounted between the sleeve and head and tends to permit a yielding rearward movement of the head with respect to the sleeve. Mounted upon the floor of the stock container are rollers 66. These rollers are spaced so that the wedge 64 may enter therebetween for a limited distance. There are two rollers one on each side of a compartment. The construction is such that when the head 64 is forced into the stall formed between the rollers so as to engage the adjacent rollers, the stock container will be maintained in a position with the corresponding slot 17 in alignment or registration with the ejector plunger.

50 In operating the device, the purchaser turns the stock container so that the compartment containing articles which he desires to purchase is in line with the opening 24. He then inserts his coin in the coin receiving slot and pulls the bar 25 outwardly. 55 In Fig. 6 a coin is shown in position so as to cause the operating bar 44 to be moved. It will be noted that the pull bar moves forwardly a limited distance before the coin engages the post 45. Upon the initial outward movement of the bar 25, the lever 56 is rocked, causing the wedge head to be pushed outwardly between the rollers and finally locking the compartment in registration with the ejector plunger. Thereafter, 60 the plunger enters the slot in the compartment and pushes the article into the delivery chute. Upon the pull bar returning, lever 56 drops by its weight and the head is retracted so as to clear the roller 66 permitting the stock container to be revolved. I have provided an additional means for centering the compartment. Mounted on the under side of the compartment floor is an annular rail 67 having indentations, one for each compartment and upstanding from the 70 plate 25 is a bracket 68. Pivotedly mounted in the bracket is an arm 69 having a roller 70 at the end thereof. The roller 70 is arranged to rest in the indentations, the spring 71 tending to hold the arm 69 so that the roller will rest in the bottom of an indentation. This will tend to cause the stock container to stop at a position such that the roller is in the lower part of the indentation and a slot 17 is in registration with the 75 ejector plunger.

What I claim is:

1. In a device of the class described, the combination of a base having a delivery passageway for articles to be vended, a stock container rotatably mounted on said base and having a plurality of compartments adapted to have the articles stacked therein, said compartments being peripherally arranged in said container, each of said compartments having a delivery outlet in the outer wall at the bottom thereof so that the container may be turned to register a selected outlet with said passageway, alignment means for finally locking a selected outlet 90 in registration with said passageway, and operating means in said base for ejecting articles from a selected compartment into said passageway, said alignment and operating means being manually operable by a 95 single movement.

2. In a vending machine, the combination of a base having a delivery passageway for articles to be vended, a stock container rotatably mounted on said base having a plurality of compartments adapted to have the articles stacked therein, said compartments being peripherally arranged in said container, each of said compartments having a delivery outlet in the outer wall at the 100 bottom so that the container may be turned to register a selected outlet with said passageway, an ejector mounted in said base comprising a plunger radially projectable into the bottom of a compartment so as to 105 eject an article from the bottom of a stack into said passageway, a pull bar for actuating said plunger having an initial independent movement with respect to said plunger and a final alignment means for locking in 110 registration said outlet and said passageway connected to said pull bar so as to be operated by the initial movement thereof.

3. In a vending machine, the combination of a base having a delivery passage way for 115

- articles to be vended, a stock container rotatably mounted on said base and having a plurality of compartments adapted to have the articles stacked therein, said compartments being peripherally arranged in said container, each of said compartments having a delivery outlet in the outer wall at the bottom thereof so that the container may be turned to register a selected outlet with said 5 passageway, an ejector mounted into said base comprising a plunger radially projectable into the bottom of a compartment so as to eject an article from the bottom of a stack into said passageway, a pull bar for 10 actuating said plunger having an initial independent movement with respect to said plunger, peripherally spaced stalls on the bottom of said container, a radially projectable head for entrance into a stall so as to 15 finally align the selected outlet and passageway, and means connecting said pull bar to said head so that the latter is operated by initial movement of said pull bar.
4. In a vending machine, the combination 20 of a base having a delivery passageway for articles to be vended, a stock container rotatably mounted on said base and having a plurality of compartments adapted to have the articles stacked therein, said compartment being peripherally arranged in said container, each of said compartments having a delivery outlet in the outer wall so that the container may be turned to register a selected outlet with said passageway, an ejector 25 mounted in said base comprising a plunger radially projectable into the bottom of a compartment so as to eject an article from the bottom of a stack into said passageway, a pull bar for actuating said structure having an initial independent movement with 30 respect to said plunger, stalls on the bottom of said container, a radially projectable head for entrance into a stall so as to finally align the selected outlet and passageway, said pull bar having a stepped upper surface, a lever 35 arranged so that one end rides on said surface, the step being so disposed that the lever riding thereon will be rocked on moving over said step and said step being disposed to rock said lever upon initial movement, said lever and head being connected so that the latter is actuated by initial movement of said pull bar.
5. In a vending machine, the combination 40 of a base having a delivery passageway for articles to be vended, a container rotatably mounted on said base having a floor, said container being divided into a plurality of peripherally arranged compartments adapted to support stacks of articles resting upon the floor, each of said compartments having a delivery outlet in the inner wall at the bottom so that the container may be turned to register a selected outlet with said passageway, said floor having radially extending 45 slots, one in each compartment and disposed below the articles stacked therein, an ejector in said base comprising a radially projectable plunger adapted to be moved into one of said slots, the end of said plunger being arranged to engage an article on its outward stroke so as to eject said article from the bottom of its stack through its outlet into said passageway and to slide beneath said stack on its return stroke.

In witness that I claim the foregoing I have hereunto subscribed my name this 3rd day of September, 1925.

JAMES E. OLVIS.
